MULTIPLE-WEB ROLL AND METHOD OF
OPERATING SAMEAlbert W. Metzner and John Q. Sherman, Dayton,
Ohio; said Metzner assignor to said ShermanApplication December 30, 1931
Serial No. 583,799 1/2

6 Claims. (Cl. 282—12)

Our invention relates to a multiple web roll used in conjunction with flat bed manifolding machines of the character disclosed and described in the patent to John Q. Sherman, No. 1,719,946, issued July 9, 1929.

In machines of this character, where several strips of paper are laid together in a superposed series and then are wound into a roll, a strip lying radially inwardly from another in a roll will stretch farther out from the roll when the series is unwound than will be the more outward strips. This circumstance has been availed of to facilitate the proper unwinding of the roll in conjunction with the operation of such machines, by virtue of the fact that, in aligning the forms printed on the several strips, over the writing bed of the machine, so that the forms, and the writing on the strips, will be in registry, one strip, being the shortest of the series, becomes the driving strip, or operative connection from the actuating means of the machine, for unwinding the roll in accordance with the successive writings to be made upon the strips, while the other strips being the longer of the series, become looped in varying degrees. The loops in an unwinding roll of this construction may facilitate the unwinding operation by the maintenance of sufficiently large loops at all times, which is necessary to the best operation of the machine. This requires a sufficient excess of length in the loose strips over the driving strip to assure the proper maintenance of the looping of the loose strips in one position at the side of the roll until all the paper is withdrawn from the roll.

In prior devices of this character, including that of the prior patent above cited, that strip or web which is the radially outermost of the series when wound into the roll being the shorter because of having traveled the greater circumference from the core, has been used as the driving strip or web, in the manner above described. This provides in the successively more radially inward strips loops of increasing degree, but only in such degree as may be had within the limits between the natural increased extension of the more radially inward webs or strips and the outer driving web or strips, inherent from the convolutions of the roll.

It is one of the objects of our invention to afford a much greater range of increased extension of the non-driving, looped strips or webs, over the extension of the tight driving strip or web, when the strips or webs have actually been aligned and registered in the machine as above explained.

Other objects will appear in the course of the

following description, which is illustrated in the accompanying drawing, in which:

Figure 1 is a side elevation of a flat bed manifolding machine embodying our invention, showing the pull-back device in its raised, inoperative position.

Figure 2 is a partial similar view, enlarged.

Figure 3 is a view similar to Figure 2, showing the pull-back device released and at the completion of its pull-back operation.

Figure 4 is a diagram better to illustrate the arrangement and mode of winding the multiple webs in the roll as indicated by dotted lines, and the unwinding of these webs from the roll into their position for use, as indicated by the solid lines.

The machine selected for purpose of illustration is shown generally in Figure 1, comprising a base and stand 1, supporting on its top the writing bed 2, associated with suitable means for guiding a typewriting machine 3 forwardly and rearwardly or transversely across the bed, as is well known in the art. Within the front end of the bed is the holding means 4, and hung from the bottom of the rear extensions 5 of the bed are the self-aligning roll mounting members comprising the bars 6. The details of construction of this mounting are unimportant from the standpoint of the invention; it being sufficient here to say that the roll A has the core 7 with a shaft 8 turning in the lower parts of the bars 6 so that the roll is free to rotate in the unwinding of the multiple webs therefrom.

As is well known in the prior art, especially in the Sherman patent hereinbefore referred to, a series of braking means 9 are arranged across between the rear extensions 5 of the bed 2, one for each strip or web a, b, c, d, e, f; the respective strip passing around the braking means 9 in such manner as to have considerable friction; so that however loose and looped the strip or web may be in its passage up from the roll A to its braking means 9, the forward extension of the strips may be stretched and held in the holding means 4, as above described; the stretching being from the braking means 9 to the holding means 4, and the purpose of course being to hold the strips tightly across the bed 2 and so that the strips will slip back into registry with the others when set over the forward aligning or holding means 4, and so that the writing by the machine 3 will be even, with resulting correctly written copies on the underlying strips, by manifolding process, as is well known in the art.

As may best be seen in Figure 4, the strips as shown by the dotted lines are extended from the

roll A with the strip *f* uppermost and most radially inward of the roll, and the other strips succeeding outward therefrom in the order *a*, *b*, *c*, *d*, *e*. But as shown by the solid lines, this innermost strip *f* is brought up around the front side of the roll A, while the other strips *a*, *b*, *c*, *d*, *e*, are swung under and upward rearwardly of the roll A, and then brought forward over the innermost strip *f*, so that they now are in the order, 10 from top to bottom, *a*, *b*, *c*, *d*, *e*, *f*, ready to be written upon. Figure 4 also will make it clear how the more outwardly lying strips *a*, *b*, *c*, *d*, *e* are unwound from the roll, initially, to a far greater extent than is the innermost strip *f*. 15 The consequence of this novel disposal of the webs or strips, having the web which is to be the bottom web of the series when the webs are written upon, not the most radially outward one of the series when in the roll A, but the radially 20 inward one, in any given convolution of the roll, is a much greater discrepancy between the extent of the radially innermost web and the successive radially outer webs than is afforded by the prior art mode of using the most radially 25 outer web of a convolution for the unwinding web, with the other webs more loose than it, merely in the proportion derived from the naturally greater extent of these webs inherent from the convoluted relation of the webs. 30 Thus, these looser looped webs, which have been initially, in the process of leading them into the machine, unwound from the roll A almost three-quarters of the roll circumference more than the driving web *f*, may have much larger 35 and looser loops, thereby attaining our object in respect of more free and proper operation of the webs in the unwinding operation, as hereinbefore stated, and the maintenance of the loops at all times in their proper position at the rear of the 40 roll.

Our improvements, as hereinbefore described, all contribute to the ease and reliability of operation of the feeding of the webs or strips to the writing bed 2 and machine 3; affording ample 45 loops in the webs, which loops are maintained down to the last unwinding convolution of the roll A, whereas in the prior arrangements, with the outermost web driving the roll, the loops practically disappeared in the last stages of unwinding; making it easy to correct a surplus withdrawal of the webs; and affording an easy and accurate working of the roll A by its self-adjusting mounting.

We have illustrated and described our preferred constructions and arrangements for effecting these objects, but it will be understood that variations may occur under various conditions of design and operation of machines of this character without departing from the scope and spirit 60 of our invention, which is set forth in the following claims:

What is claimed is:

1. The method of forming a roll of multiple webs to be unwound for use in a certain final 65 superposed series of desired sequence, consisting in superposing the webs in a preliminary series with the particular web that is to be the bottom web in the sequence of the final series at the top of the preliminary series, winding said preliminary series of webs into a roll with said particular web radially inward from any other web of the series, and unwinding said roll into said final series with said particular web less slack than any other web unwinding therewith, and acting 70 as the rotator of the roll. 75

2. A roll formed of a core and a convoluted series of webs mounted on said core for unwinding to bring said series of webs into extended condition for making manifold copies on the several webs, the radially innermost web in the convolutions being unwound from the roll in its initial passage therefrom to a lesser degree than any other web, and the advanced portions of the webs being in registry to correspondingly receive their copies, the diameter of the core relative to the travel of the webs being such that said innermost web passes from the roll under tension as the driver of the roll, while said any other web passes from the roll in a slack looped condition throughout the unwinding of the roll. 15

3. A roll formed of a core and a convoluted series of more than two webs mounted on said core for unwinding to bring said series of webs into extended condition for making manifold copies on the several webs, the radially innermost web in the convolutions being unwound from the roll in its initial passage therefrom to a lesser degree than any other webs, and the advanced terminal portions of the webs being in registry to correspondingly receive their copies, the diameter 20 of the core relative to the travel of the webs being such that said innermost web passes from the roll under tension as the driver of the roll, while said other webs pass from the roll in slack looped condition throughout the unwinding of the roll. 30

4. A method of unwinding a roll comprising a plurality of superposed strips of stationery material wound together, which comprises positively feeding and tensioning the innermost one of said strips as wound into the roll, while providing slackness in the others of said strips initially, and continuing the unwinding operation as described whereby the continuous shortness of the said innermost strip is relied upon continuously to maintain the slackness in the others of said strips. 35

5. A method of unwinding a roll comprising superposed strips of stationery material so as to continuously avoid tension in all but one of said strips, which comprises passing the innermost of said strips as wound into the roll around said roll so as to remove said strip substantially tangentially therefrom at a side removed from the side of removal of the other of said strips and feeding said innermost strip under tension whereby slackness may be maintained in the others of said strips. 50

6. A method of feeding a plurality of strips of stationery which have been wound into a single roll in superposed position, said strips each containing a plurality of individual stationery forms of equal length which method consists in ascertaining which of said strips occupied the innermost position as wound into the roll, placing a form of said innermost strip in an operating position, assembling forms of the others of said strips in said operating position in such a way as to leave slackness in said others of said strips between said operating position and said roll, and simultaneously feeding said strips form by form through said operating position whereby only the said innermost of said strips is tensioned against said roll, the others of said strips being maintained in a slack condition adjacent said roll by 70 the continuous shortness of said innermost strip during the unwinding operation. 60
